CLAIM

The ornamental design for the washer, as shown and described.

DESCRIPTION

FIG. 1 is a top perspective view of the washer showing the design in an environment of use;

FIG. 2 is a top perspective view of the washer of FIG. 1;

FIG. 3 is a top plan view of the washer of FIG. 1;

FIG. 4 is a bottom plan view of the washer of FIG. 1;

FIG. 5 is a side elevation view of the washer of FIG. 1; and, FIG. 6 is a bottom perspective view of the washer of FIG. 1.

The broken lines represent environment and form no part of the claim.
